Primary Examiner — Kimberly Barnes(74) *Attorney, Agent, or Firm* — William H. Honaker;
Dickinson Wright PLLC(57) **CLAIM**

The ornamental design for a bump cap, as shown and described.

DESCRIPTION

FIG. 1 is a perspective view of a bump cap showing our new design.

FIG. 2 is a front view thereof.

FIG. 3 is a side view thereof.

FIG. 4 is a side view thereof.

FIG. 5 is a rear view thereof.

FIG. 6 is a top view thereof; and,

FIG. 7 is a bottom view thereof.

The broken lines in the drawings depict portions of the bump cap that form no part of the claimed design.
